H. G. WATSON

FLASH LIGHT

Original Filed June 7, 1924

H. G. Watson,
Inventor

By

James A. O'Brien.

Attorney

UNITED STATES PATENT OFFICE.

HARRY G. WATSON, OF FAIRBANKS, TERRITORY OF ALASKA.

FLASH LIGHT.

Application filed June 7, 1924, Serial No. 718,586. Renewed August 26, 1925.

To all whom it may concern:

Be it known that I, HARRY G. WATSON, a citizen of the United States, residing at Fairbanks, Territory of Alaska, have invented certain new and useful Improvements in Flash Lights, of which the following is a specification.

This invention relates to flashlights, and it consists in the novel features hereinafter described and claimed.

An object of the invention is to provide, in a flashlight structure, means for generating an electric current, and means for conducting the current to a bulb provided upon the device, there also being provided a spring means adapted to be manually wound, and which is operatively connected with the generator.

In the accompanying drawing,

Figure 1 is a sectional view of the flashlight.

Figure 2 is a transverse sectional view of the flashlight, taken on the line 2—2 of Figure 1.

As illustrated in the accompanying drawing, the flashlight comprises a casing 1, which is of general elliptical shape. A hanger 2 is provided in the casing 1, and a bracket 3 is mounted upon said hanger. A socket 4 is carried by the bracket 3 and is adapted to receive a lamp bulb 5. A reflector 6 is mounted upon the socket 4, and houses the bulb 5 and passes through the side of the casing 1. A lens 7 is carried at the outer portion of the reflector 6. A generator 8 is mounted upon the hanger 2, and its shaft is provided with a gear wheel 9, which is operatively connected by means of a train of gear wheels 10, with a shaft 11, which is journalled in the casing 1. The shaft 11 is disposed transversely across a spring actuated barrel 12 which is housed within the casing 1. The terminal gear wheel of the train 10 meshes with a gear wheel 13, which is mounted upon the side of the spring barrel 12. A train of gear

wheels 14 is connected with the barrel 12, and a holding pawl 15 is adapted to engage one of the gear wheels 14, whereby the train of gear wheels 14 is held against reverse rotation. A crank handle 16 is located exteriorly of the casing 1 and is operatively connected with one of the terminal gear wheels of the train 14, as best shown in Figure 2 of the drawings.

When the spring of the barrel 12 is wound up by turning the crank handle 16, rotary movement is transmitted from the barrel through the train of gear wheels 10, to the shaft of the generator 8, whereby an electric current is generated, and the said current passes from the generator over conductor wires 17 to the lamp bulb 5, which is illuminated. The lamp bulb 5 will remain illuminated, so long as the spring of the barrel 12 is in a wound condition, and in practice, it is found that the bulb will remain in an illuminated condition, for a period of nine or ten minutes.

Having described the invention, what is claimed is:

In combination, a casing, a hanger depending from an intermediate portion of the top of the casing, shafts journaled between the inner end of the hanger and one end of the casing, a bracket extending laterally of the intermediate portion of the hanger and terminating in a socket, an electric bulb in the socket, wires electrically connecting the bulb and the generator, said generator being mounted on the hanger between the shafts and the bracket, a pinion for operating the generator, a train of gears associated with the shaft and one meshing with the pinion, and a motor in the casing on the opposite side of the hanger than is disposed the bracket, and one of said shafts operatively connected with the motor.

In testimony whereof I affix my signature.

HARRY G. WATSON.
